UNITED STATES PATENT OFFICE.

CHARLES E. CALLENDAR AND JOHN V. GITTINGER, OF TIFFIN, OHIO.

BATTERY-TERMINAL CONNECTION.

Application filed January 11, 1924. Serial No. 685,675.

To all whom it may concern:

Be it known that we, CHARLES E. CALLENDAR and JOHN V. GITTINGER, citizens of the United States, residing at Tiffin, in the county of Seneca and State of Ohio, have invented certain new and useful Improvements in Battery-Terminal Connections, of which the following is a specification.

This invention relates to battery terminal connections and it consists in the novel features hereinafter described and claimed.

An object of the invention is to provide a battery terminal connection of simple and durable structure adapted to securely hold the wiring and to make a tight, intimate and effectual electric connection at the terminal and thereby preventing short circuit.

A further object of the invention is to provide a terminal connection which may be easily and quickly applied to or removed from the terminal and thereby saving labor and time in the application and detachment. Also the speed of detachment may be the means of preventing disastrous fire which might result from short circuit and in the event time is consumed in breaking the electric connection with the batteries.

In the accompanying drawing—

Figure 1 is a plan view of the battery terminal connection.

Figure 2 is a bottom plan view thereof and

Figure 3 is a central longitudinal sectional view of the device.

The battery terminal connection comprises a collar 1 having an opening 2 passing therethrough. When applied the opening 2 is adapted to receive the terminal of the battery (not shown).

A sleeve portion 3 is integrally joined with the collar 1 and the length of the sleeve is disposed transversely of the axis of the opening 2 in the collar. The sleeve is disposed at one side of the collar and is located

at a point midway between the ends of the collar. The sleeve is adapted to receive and retain the wire (not shown) which connects the battery terminal electrically with the ignition or light systems, (also not shown).

The collar 1 is provided at one side of the opening 2 therein with a lateral extension 4 provided with a threaded bore 4' which receives a screw bolt 5. The axis of the bore is disposed parallel with the axis of the opening through the collar. At one side 55 the bore communicates with the opening throughout the length of the bore and opening.

The screw bolt is provided with a head 6 which is disposed over the lateral extension 60 4 and which extends partially over the opening in the collar. Part of the thread of the screw enters the opening in the collar.

The screw is slightly flattened at one side as at 7. When the collar is slipped over the battery terminal the flattened side of the screw is in alignment with the wall surface of the opening in the collar. When the collar is in position upon the terminal the screw bolt is given a partial turn which 70 causes the thread of the screw to bite into the terminal and secures the collar upon the terminal. At the same time the thread of the screw enters the terminal and produces a good electrical contact. To remove the 75 connection from the terminal the operation above described is reversed.

Having described the invention what is claimed is—

A battery terminal connection comprising 80 a collar provided at one side with a lateral extension having a threaded bore disposed parallel to and communicating with the opening in the collar and a screw threaded in said bore and engageable with the terminal to bind the collar thereon, said screw having a flattened side portion disposed in alignment with the wall of the opening in the collar in engaging the latter with the terminal and a head disposed over said 85 lateral extension.

In testimony whereof we affix our signatures.

CHARLES E. CALLENDAR.
JOHN V. GITTINGER.
